UNITED STATES PATENT OFFICE

HENRY E. BARROLL, OF CHICAGO, ILLINOIS, ASSIGNOR TO HENRY BARROLL & CO., INC.,
OF CHICAGO, ILLINOIS, A CORPORATION OF NEW YORK

POURING NOZZLE

Application filed January 31, 1929. Serial No. 336,492.

My invention relates to means for sealing pouring containers or pouring nozzles and has for one particular purpose to provide a means of and method for inserting within 5 the pouring nozzle a seal which is enclosed within or covered by the normal removable closure for the pouring nozzle. Another object is to provide such a seal which shall be relatively easily removable, but the removal 10 of which shall be clearly apparent to a subsequent user, the seal being difficult or impossible to replace once it has been removed. Other objects will appear from time to time 15 in the course of the specification and claims.

I illustrate my invention more or less diagrammatically in the accompanying drawing, wherein:

Figure 1 is a more or less diagrammatic 20 vertical section through a nozzle about to be sealed, illustrating the tool and the sealing member;

Figure 2 is a similar section illustrating the 25 tool at or near the termination of its downward sealing movement;

Figure 3 is a similar section illustrating the seal in final position and the normal closure 30 cap in position on the nozzle;

Figure 4 is a similar section illustrating the 35 removal of the cap;

Figure 5 is a similar section through a 40 variant form of nozzle illustrating the cap in initial position; and

Figure 6 illustrates the structure of Figure 45 5 after the cap has been expanded into final position.

Like parts are indicated by like symbols throughout the specification and drawing.

Referring first to the method and device 50 illustrated in Figures 1 to 4 inclusive A generally indicates any suitable container, for example a can, to which has been secured the pouring nozzle A¹ with its cap engaging upper flange A² adapted to receive the cap shown as A³ in Figure 3. Note that in the form herein shown the cross-section of the passage or nozzle A¹ decreases progressively towards the bottom of the nozzle. In normal practice there will be a slight ledge as 55 at A⁴ in Figure 1.

The sealing member generally indicated as

B includes a central portion B¹ surrounded by the channel B² with the circumferential upwardly bent portion or flange B³, the latter being adapted to engage the inner wall of the nozzle passage A¹.

In seating the seal in place I may employ any suitable tool, for example the one generally indicated as C in Figures 1 and 2 which has a central depression C¹ adapted to receive the portion B¹ of the seal, and the circumferential flange C² adapted to penetrate the channel B² of the seal. When the tool is thrust into the lower position, as shown in Figure 2, it carries the sealing member B downwardly through the nozzle B¹ and the circumferential flange B³ is bent into the position in which it is shown in Figures 2 and 3. The result, the stock being thin and flexible, is a firm sealing or locking engagement between the flange B³ and the nozzle wall A¹ which continues after the tool is withdrawn. The downward movement of the tool may be limited by any suitable means not herein shown. Where a hand tool is employed the projection A⁴ may serve to limit or help to limit the downward movement of the tool and engagement with it will serve as an indication to the operator that the tool has reached the proper lower position.

When the tool has been withdrawn the container and its contents are sealed and the usual closure cap A³ may be screwed into place or otherwise suitably secured to the head member or flange A².

When the user wishes to remove the seal he unscrews and removes the cap A³ and then inserts some tool for example a screwdriver down through the nozzle A¹ into the channel B². In Figure 4 a practical initial position of the tool is indicated in dotted line. The operator then tilts the tool to the full line position and the result is such a deformation of the seal as will cause it to flip out or will permit it to be readily removed. In practically all cases the seal may be removed upon contact with the screwdriver end and the can is then usable in the usual fashion. Once the sealing has been deformed the individual seal may be thrust back into position, but it is sufficiently thin

to record any contact of any force and subsequent users will immediately see that the can has been tampered with.

Referring to the method and seal of Figures 5 and 6, I may employ a can in which the nozzle portion D has an upwardly turned flange D¹ at the bottom. The nozzle thus formed may of course be soldered to the top of the container A as at D² and if necessary the periphery of the aperture into which it is soldered may be channeled as at D³. In any case the seal member E, generally identical with the seal member B above described, is thrust into position or dropped into position, but with the central portion E¹ down and the channel E² down the flanges or edges E³ penetrating the channel formed between the wall D and the flange D¹.

This initial position of the seal is illustrated in Figure 5. Any suitable means, for example a tool, with expansion rollers, may be employed to expand or compress the parts together, to the position shown in Figure 6. The result is a seal which has to be punched out or thrust into the interior of the can. Where such punching out leaves a ragged edge, this edge is substantially enclosed by the nozzle D and the user is not likely to be damaged by sharp metal edges.

I claim:

1. The combination with a dispensing container having a nozzle and a closure cap for said nozzle, of a sealing member adapted to be inserted within said nozzle, to a level beneath the closure cap, said sealing member including a central portion having a channel about the edge thereof, said channel being bounded on its outer side by a peripheral flange or wall inclined in relation to the central portion of the sealing member.

2. The combination with a dispensing container having a nozzle and a closure cap for said nozzle, of a sealing member adapted to be inserted within said nozzle to a level beneath the closure cap, said sealing member including a central portion having a channel about the edge thereof, said channel being bounded on its outer side by a peripheral flange or wall adapted for frictional engagement with the inner wall of the nozzle.

Signed at Chicago, county of Cook and State of Illinois, this 23rd day of January, 1929.

HENRY E. BARROLL.
